ALBERT J. LOEPSINGER, OF PROVIDENCE, RHODE ISLAND, ASSIGNOR TO GENERAL FIRE EXTINGUISHER COMPANY, OF NEW YORK, N. Y., A CORPORATION OF NEW YORK.

DRY-PIPE VALVE.

1,196,875.

Specification of Letters Patent. Patented Sept. 5, 1916.

Application filed November 17, 1910. Serial No. 592,811.

To all whom it may concern:

Be it known that I, ALBERT J. LOEPSINGER, of Providence, in the county of Providence and State of Rhode Island, have invented 5 certain new and useful Improvements in Dry-Pipe Valves; and I do hereby declare the following specification, taken in connection with the accompanying drawings, forming a part of the same, to be a full, clear, and 10 exact description thereof.

The present invention relates to improvements in dry pipe valves for use in automatic sprinkler systems.

In an application of even date herewith I 15 have shown and described two forms of dry pipe valves, the characteristic feature of each of said forms being that the air-valve and the water-valve close the waterway at each valve when seated and are both mounted 20 outside of the waterway to swing about a common center, and with the axis of the air-valve located at a greater distance from said common center than the axis of the water-valve, and so that thereby there will be a correspondingly greater leverage through which 25 the air-pressure acts as compared with the leverage through which the water-pressure acts. In one form of valve shown in said application the air-valve and the water-valve, together with the seats therefor, are arranged in different planes and at an oblique angle to each other, said air-valve and water-valve being rigidly connected together by a connecting bridge-piece.

30 The object of the present invention is to improve the construction of such form of dry pipe valve.

To that end the present invention consists primarily of a dry pipe valve having the 40 general characteristics above referred to and further characterized by the connection of the air valve and the water valve in such manner as to provide for a relative rocking movement between them, whereby the simultaneous seating of both valves is facilitated and the action of the pressures thereon is such as to prevent the greater leverage of the air valve from becoming ineffective when the valves are seated.

45 The invention further consists in certain

constructions, combinations, and arrangement of parts hereinafter described and claimed.

Referring to the drawings, Figure 1 is a longitudinal sectional view of a dry pipe 55 valve embodying the invention, and Fig. 2 is a sectional detail at right angles to the section shown in Fig. 1.

The valve-casing comprises two parts 1 and 2, the abutting faces of which are formed 60 at an angle to the axis of the water-way, as shown, the two parts being secured together by bolts 3. The part 1 of the valve-casing is provided with an inlet opening 4 adapted to communicate with the water supply pipe, 65 and the part 2 is provided with an outlet opening 5 adapted to communicate with the riser of a sprinkler system. The inlet opening is provided with a valve-seat 6 for the water-valve 7, while the part 1 of the valve-casing is provided with an angularly arranged valve-seat 8 for the air-valve 9.

The water-valve 7 and the air-valve 9 are arranged at a corresponding angle to each other, and said water-valve and air-valve are 75 connected together in a manner to be herein-after described. The two valves thus connected together are carried by a swinging arm 11, one end of which is secured to the air-valve, the other end of said arm being 80 pivoted to the part 1 of the valve casing by a pivot-pin 12. The arm 11 in the construction shown is bent and so as to bring the pivot 12 below the water-level 7. This construction of the arm 11 and location of the 85 pivot 12 not only insures that the distance from the pivot to the axis of the air-valve shall be greater than the distance from the pivot to the axis of the water-valve, but also serves to reduce the space required for 90 the valves to swing in, thereby correspondingly reducing the size of the valve-casing. The air-valve 9 is preferably provided with an annular lip of flexible or yielding material, which may be secured to the main body 95 of said air-valve by screws 14, said lip 13 constituting the part which seats upon the valve-seat 8.

Preferably the arm 11 is provided with a series of teeth adapted to be engaged by a 100

5 pivoted hook or latch 16 for the purpose of holding the valve structure in open position and preventing it from accidentally closing again after it is once opened or partially 10 opened. The valve casing is provided with a hand-hole cover 17, through which the valve structure may be inserted in or removed from the valve-casing, and in the construction shown the hook or latch 16 is pivoted to this 15 hand-hole cover. Another hand-hole cover 18 indicated by dotted lines is provided to permit access to the interior of the valve casing for the purpose of cleaning the valve-seats and resetting the valves. A drip opening 20 communicates with the intermediate chamber between the two valve-seats for the purpose of taking care of leakage past either the water-valve or the air-valve, said drip opening being preferably provided with the usual drip-valve 19, as shown.

Referring now to the manner of connecting together the water-valve and the air-valve, the water-valve 7 is provided with an upwardly extending boss or projection 25, while the air-valve is provided with a downwardly extending projection 21, preferably of web form. The projection 20 is provided with a hemispherical recess in its upper face, and the projection 21 is provided with a correspondingly hemispherical recess in its lower face, said recesses together forming a pocket for an interposed ball 22. The projection 20 is provided with a laterally extending flange 23 and the projection 21 is provided with a corresponding laterally projecting flange 24, each of said flanges being provided with holes or perforations for the reception of bolts 25. Each of these bolts is preferably provided 30 with a shoulder 26 intermediate its ends, and the lower end of each bolt which is thus of reduced diameter is made to substantially fit the corresponding hole in the flange 23. The corresponding hole in the flange 24, however, is made somewhat larger in diameter than the diameter of the upper portion of said bolt, and so that there may be a limited transverse movement of the bolt in said hole. Each of the bolts is provided 35 at its lower end below the flange 23 with a nut 27, by means of which the bolts are secured to said flange.

With the construction above described, when the air-valve and water-valve are 40 seated and air-pressure is pumped up in the sprinkler system, the water-valve will be held closed by the air-pressure in the system acting upon the air-valve, and with said construction, as will be understood, the air-pressure required to hold the water-valve closed may be materially less than the water-pressure which is acting on the water-valve and tending to open the same.

When the air-pressure in the system becomes reduced below the predetermined point, as by the opening of one or more 45 sprinklers, and so that such air-pressure is no longer able to hold the water-valve closed, the water-pressure acting upon the water-valve will serve to open the same, and 50 in thus opening, the water-valve and the air-valve will both be caused to swing about a common center, and in so swinging will be moved to a position wholly to one side of the water-way, and so as to leave a free 55 and unobstructed passage for the water in flowing to the sprinkler system. As the water-valve and air-valve are thus swung about a common center, the hook or latch 16 automatically engages successively the 60 teeth 15, and so that said latch will serve to hold the valves in their open position and to prevent their being accidentally closed.

In the present construction, as will be seen, the water-valve, instead of being rigidly connected to the air-valve, is capable 65 of a limited rocking or tipping movement independent of and with relation to said air-valve. This serves to facilitate the simultaneous seating of the two valves. 70 Moreover, since the pivotal connection between the valves is located at one side of the axis of the air valve the action of the air pressure on said valve results in a relative rocking movement of the two valves 75 sufficient to take up the looseness of fit which, in order to insure a free pivotal action when the valves open, is customarily provided at the pivot 12. Thus when the valves are closed the valve-carrying arm is 80 always maintained in contact with said pivot, and this is important for the reason that in the absence of such contact the valve-carrying arm would become functionless as a means for determining the leverage 85 through which the pressures on the valves act and consequently the effective or resultant pressure tending to hold the valves closed when seated would depend upon their areas alone. Such pressure, however, would 90 ordinarily be insufficient to hold the water valve on its seat, and in such case said valve would be repeatedly subjected to opening movements of sufficient extent to produce contact between the valve-carrying arm and 95 its pivot, with the result that considerable leakage would inevitably occur. Such a result is prevented by the arrangement above described, since the axis of the air valve passes the pivotal bearing 22 on the opposite side of the latter from the pivot 12 and hence the air pressure causes the arm 11 to rock until it comes in contact with the pivot 12 at approximately the under side of the latter, so that the intended leverage of 120 both valves is maintained and any valve-

opening movement whatever is necessarily a swinging movement about said pivot.

By connecting the water-valve and air-valve together by the bolt construction shown and described, a sufficient capacity for the swinging or tipping of the air-valve is provided, while the extent of such rocking or tipping movement is limited, thereby serving to maintain the water-valve in substantially its normal relation to the air-valve, when said valves are opened, and so that in reseating the valves no special or separate manipulation of the water-valve will be required, but instead said water-valve will be brought properly upon its seat by simply swinging back the arm 11 to its normal position.

What I claim as my invention and desire to secure by Letters Patent is:

- 20 1. A dry-pipe valve having in combination a water-valve and an air-valve with valve-seats therefor, said valves being arranged at an angle to each other and mounted to swing about a common center, and being connected together by a pivotal connection, with the axis of the air-valve extending outside of such pivotal connection on the side away from said common center.
- 25 2. A dry-pipe valve having in combination a water-valve and an air-valve with valve-seats therefor, said valves being arranged at an angle to each other and mounted to swing about a common center, and being connected together by a pivotal connection, with the axis of the air-valve extending outside of said pivotal connection on the side away from said common center and with a means for yielding engagement between said air-valve and its seat.
- 30 3. A dry-pipe valve having in combination a water-valve and an air-valve with valve-seats therefor, said valves being arranged at an angle to each other and mounted to swing about a common center, and being connected together by a ball and socket joint, with the axis of the air-valve extending to one side of the center of said ball on the side away from said common center.
- 35 4. A dry-pipe valve comprising an air valve, a water valve carried thereby and pivotally connected thereto, said valves being arranged at an oblique angle to each other and adapted to close the water-way at each valve when seated, and valve-carrying means connected to the air valve and mounted to swing about a center with respect to which the air valve has greater leverage than the water valve.
- 40 5. A dry-pipe valve comprising an air valve and a water valve pivotally connected to each other at one side of the axis of the air valve and arranged to close the water-way at each valve when seated, one of said

valves having a yielding engagement with its seat, and valve-carrying means connected to the latter valve and mounted to swing about a center with respect to which the air valve has greater leverage than the water valve.

6. A dry-pipe valve comprising a casing, an arm pivotally mounted therein, outside of the waterway, an air valve carried by said arm, a water valve carried by the air valve and pivotally connected thereto at one side of the axis of the latter, and valve seats at each of which the water-way is closed by the corresponding valve when seated, the pivotal axis of said arm being so located that the air valve has greater leverage than the water valve.

80 7. A dry-pipe valve comprising a casing, an arm pivotally mounted therein, outside of the water-way, an air valve carried by said arm, a water valve carried by the air valve at an oblique angle thereto and having a universal-joint connection therewith, and valve seats at each of which the water-way is closed by the corresponding valve when seated, the pivotal axis of said arm being so located that the air valve has greater leverage than the water valve.

85 8. A dry-pipe valve comprising a casing containing an air valve seat arranged at an inclination with respect to the water-way and a water valve seat extending transversely with respect to the water-way, said seats being located one beyond the other with the water-way passing through both of them, a pivotally-mounted arm located outside of the valve seats and movable toward and away from the latter, an air valve carried by said arm, and a water valve carried by the air valve and having a pivotal connection therewith between the axis of the latter and the pivotal axis of said arm.

90 9. A dry-pipe valve comprising a casing containing an air valve seat arranged at an inclination with respect to the water-way and a water valve seat extending transversely with respect to the water-way, said seats being located one beyond the other with the water-way passing through both of them, a pivotally-mounted arm located outside of the valve seats and movable toward and away from the latter, an air valve rigidly secured to said arm and having means for yielding engagement with its seat, and a water valve carried by the air valve and having a pivotal connection therewith between the axis of the latter and the pivotal axis of said arm.

105 10. A dry-pipe valve comprising a casing providing an upwardly-extending water-way and containing a slanting air valve seat and a transversely-extending water valve seat, said seats being located one above the

other with the water-way passing through both of them, a pivotally-mounted arm located outside of the valve seats and movable toward and away from the latter, an air valve rigidly secured to said arm and having a yielding margin, and a water valve carried by the air valve and having a universal-

joint connection therewith between the axis of the air valve and the pivotal axis of said arm.
